MULTI-PLY WOOD BAKER'S PEEL

Henry L. Schroeder, Chicago, Ill.

Application June 3, 1935, Serial No. 24,595

5 Claims. (Cl. 107—67)

The invention relates to a novel construction of multi-ply wood strips united at various angles to produce structures of unusual and novel formation, particularly desirable for use in the manufacture of peel blades which may be used by bakers for the proofing of bread, the handling of crackers or any other uses to which peel blades may be put.

My improved structure is particularly designed and adapted to produce a composite wood blade of a plurality of veneers or plywood so arranged as to practically eliminate splitting and to positively prevent warping under the unusual conditions to which bakers' peels are usually subjected in their uses connected with baking ovens, the construction being also adapted to greatly prolong the wearing qualities and the life of peels made from composite wood blanks constructed in accordance with the invention.

It is a further object of the invention to provide an improved construction of a composite blade blank of veneer or plywood presenting an active point or engaging edge for a peel blade that will be re-enforced by a novel arrangement of the grain of the sheets of veneer or plywood used in making the composite blades whereby to prolong the life of the blade by increasing the wearing qualities at the work engaging end or point of the blade, at the same time rendering splitting of the blade throughout the length of its useful life practically impossible.

Other objects of the invention will appear from the following description which is directed to the preferred embodiment of my improved peel blade blank construction, reference being had to the drawing forming a part of the specification, the features of novelty being specifically set forth in the appended claims.

In the said drawing:

Fig. 1 is a plan view of a peel blade blank constructed in accordance with my invention, portions of the composite layers of the blank being broken away to disclose the arrangement of the grain of the wood sections.

Fig. 2 is a side elevation view of the blank of Fig. 1.

Fig. 3 is a modified form of the composite blank of Figs. 1 and 2 showing a three-ply blade as contrasted with the five-ply construction of Figs. 1 and 2, and Fig. 4 is a side elevation view of the construction shown in Fig. 3.

Fig. 5 is a further modification of the invention as applied only to the point or work engaging, thinned, forward end of a wood peel blade, and

Fig. 6 is a side elevation of the same.

In the top plan view of the preferred form of the completed composite peel blade blank of Fig. 1 as well as in the modifications of the same as shown in Figs. 3 and 5, portions of the lamina or plywood, superposed layers of which the blanks are formed, are shown broken away to disclose the arrangement of the grain of the wood sheets or lamina of the respective blade blanks, while the side elevation views of these respective figures as shown in Figs. 2, 4 and 6, only the arrangement of the lamina or layers is attempted to be shown and the graining and the broken away portions are omitted and it will be understood that the preferred form of blank of Figs. 1 and 2 as well as the modified forms shown in Figs. 3, 4 and 5 and 6, respectively, represent substantially completed wood blades ready for use in a commercial peel with the exception of whatever recessing or cutting or other provisions may be provided at the heel end of the blade for the attachment of the usual detachable handle used in manipulating the peel blade, all of which are in the present embodiment omitted since the same forms no part of the invention and it will suffice to say that any form of conventional handle or handle attaching means may be provided at the heel end of the improved peel blades embodying my invention.

With reference to the top plan views of the forms of the blades shown in Figs. 1 and 3 especially it should be noted that only the top surfaces of the exposed lamina or layers of the plywood are intended to be shown for the purpose of illustrating the direction of the grain therein. In the form of a multiply peel blade blank illustrated in Figs. 1 and 2, it will be seen that a five ply structure is provided in which the intermediate, longitudinal core 10 is shown as of substantially equal thickness throughout the area of the blade and that this relatively thicker core is substantially the base or foundation of the composite structure. I prefer to have the grain of the longitudinal core portion 10 extend substantially parallel with the longitudinal axis of the blade as shown most clearly in Fig. 1 and to this portion I secure by means of glue or other suitable adhesive on both the flat surfaces thereof the veneer lamina or layers 11 and 12 respectively. These sheets 11, 12 of thin wood are so secured to the respective upper and lower surfaces of the longitudinally grained core member 10 as to have their respective grains running substantially at a 45° angle to the direction of the extension of the grain of the intermediate core 10 and their respective grains will then extend substantially at a 55

90° angle to each other, all as illustrated in Fig. 1.

After the securement of the layers 11 and 12 in the aforesaid manner to the intermediate core 10, this three ply composite structure has applied on the outer flat surfaces thereof similar thin plies or layers of wood 13 and 14 respectively, both of which also have their grain directions to extend substantially at 45° angles to the extension of the grain of the intermediate longitudinal core section 10 but in order to secure strength and ability to withstand warping and splitting strains as shown in Fig. 1, I arrange the grain of these outside layers 13 and 14 so that their respective grains will extend substantially at right angles or an angle of 90° to the grain of the before described layers 11 and 12, to which these are firmly united by glue joints in the manner in which plywood lamina or layers are commonly united and since peel blades of the described character are subjected frequently to relatively high degrees of heat in baking ovens, obviously care must be exercised to select well known forms of glue or adhesive that will not be deleteriously effected or softened by heat.

With the five ply blade constructed of the intermediate core 10 and the lamina or layers 11 to 14 inclusive as described, a composite blade of rectangular form as illustrated in Fig. 1 is then ready for incorporation of the handle attaching means after it is suitably pointed at the end opposite the heel or handle attaching portion where it is preferably beveled or sanded to a pointed condition as illustrated in Figs. 1 and 2 where it will be seen that the beveling and sanding operation will polish and finish the blade so that the forward edge of the composite blade will be beveled to a comparatively sharp or knife-like edge, the beveling being done at an angle that will expose, as shown in Figs. 1 and 2, the beveled, pointed, forward and work engaging portion 10 for a short distance and will also expose the portion of the forward beveled surface of the lamina or layers 11 and 12 next the intermediate core 10, the beveling operation preferably extending back and thinning down the forward portions of the outer layers 13 and 14 somewhat in the manner indicated at Figs. 1 and 2.

Extensive experiment and experience on my part with bakers' peel blades constructed in accordance with the before described features of construction as illustrated in Figs. 1 and 2 has demonstrated that a peel blade constructed in this manner has great strength and rigidity and will not split and become deleteriously effected, particularly at the point of the blade, thus giving such peel blades unexpectedly long life under the difficult conditions of heat and rough oven bottom conditions where they are commonly used.

I find, for example, that with a five ply composite peel blade constructed as above described and illustrated in connection with Figs. 1 and 2 that while the exposed and sharpened forward or pointed extremity of the intermediate core 10 may ultimately wear off and down to the co-operating thin pointed portions of the layers 11 and 12, nevertheless the construction of the lamina or layers of the blade at the point where the most severe abrading and splitting effect upon the blade takes place, will ordinarily not permit the peel to split or warp at the point but the construction will retain and hold the thin projecting intermediate part of the core portion 10 until it is substantially worn away and any tendency towards splitting of the core 10 will

be effectively resisted by the relative 90° angularities of grain the layers or lamina 11, 12 which latter will be further reenforced by their outer protective coverings 13 and 14 which, as described, have their grain extensions arranged at substantially right angles to the grain extensions of the layers 11 and 12 to which they are secured.

This improved construction, therefore, provides an improved peel blade that may be used and worn almost indefinitely and abrasion and wear will ordinarily only tend to shorten the length of the blade without permitting splitting and warping so that the maximum life of the blade may be secured before replacements are necessary.

The 45° arrangement of angularity of the respective layers or lamina of my ply board blade also tend to prevent undue splitting of the outer protective layers 13, 14 and 11, 12 since the abrading effect, due to the contact of the point with the oven bottom, appears merely to wear away the wood particles of the structure without permitting the splitting of the same at the point where the most destructive effects of peel blade wear usually take place, rendering them ordinarily short-lived and subject to frequent and rapid replacements.

In the form of the invention shown in Figs. 3 and 4, a cheaper lighter but very efficient three-ply form of composite blade is illustrated in 30 which an inner core 16 is illustrated as tapered from the heel end toward the point of the composite blade. As shown in Fig. 3, the grain of the inner tapered core 16 will preferably extend longitudinally of the blade, and the core 16 as well as the before mentioned core 10 of the form of blade shown in Figs. 1 and 2 may be made of very light wood as balsa wood or corkwood and the outer lamina or layers of wood of firmer texture or grain so that in each case, the exposed surfaces of the blade will be well protected by the layers of firmer wood.

In the form with the tapered inner core shown in Figs. 3 and 4 I prefer to terminate the inner core of the normal length of the blade in the manner illustrated thus bringing the material at the point of the core 16 to a very thin dimension as indicated at 18. When the three ply construction is used, the grain of the outer layers or lamina as indicated at 19, 20 will be arranged as shown to 50 extend at an approximate angle of 45° to the grain of the core 16 and at the point of the blade, the layers 19 and 20 will extend beyond the terminus of the thinned end 18 of the inner core 16 and be suitably glued together and sanded 55 and sharpened at the forward point as indicated at 21, Fig. 4.

My experiments and experience with peel blades constructed in accordance with the invention has taught me that the importance of the invention 60 resides in the novel arrangement of the grain of the reenforcing materials or outer lamina of the blade in relation to each other and in relation to the grain of the inner core and I have found that a light, cheap form of peel blade may be constructed embodying the principles of my invention, with respect to the construction toward the point of the blade where the most destructive wear upon the blade takes place, as illustrated in Figs. 5 and 6 in which a substantially solid peel 65 blade blank 22 is shown formed of an integral piece of wood, preferably having the grain extending longitudinally and from the heel end toward the point thereof. Such a peel blade blank may be of very light and soft or relatively 70

not firm wood having the point thereof reenforced by ply wood layers or lamina 23, 24 similar to the before described outer layers or lamina of the blanks of Figs. 1 to 4 inclusive. The reinforcing point members 23, 24 may be attached to the beveled or pointed end of the blank 22 by recessing it in the manner indicated in Figs. 5 and 6, the layers 23 and 24 having their grain extending substantially at right angles to each other and at substantially an angle of 45° to the extension of the grain of the blade member 22, and these reinforcing point layers 23, 24 may be suitably glued at the point of the blank 22 and overlap and extend beyond the same in the manner illustrated where they will be brought together and united by adhesive and sharpened and sanded to form a suitable point for the blade.

Such a blade point construction as in the case of the similar construction shown in the modified form of Figs. 3 and 4 will admit of long wear. The angular extension of the grain in the reinforcing point layers 23, 24, when these parts are suitably glued together will effectively resist splitting or abrading until the members 23 and 24 are worn back to expose the intermediate sharpened point of the blade body section 22 when the operation of the same may be continued as with the form of Figs. 1 and 2 until the blade is substantially worn out.

As indicated in connection with the form of the three ply reinforced point of the blade of Figs. 3 and 4, when extremely soft lumber is used in the formation of the peel blade body 22, the reinforcing point layers 23, 24 may be made flush with the outer surfaces of the body portion 22 by application of pressure upon the parts when they are being glued together, but in the event that a more firm or harder material is used for the body 22, recessing by cutting or other similar operation may be necessary to offset the body portion 22 for co-operation with the pointed layers 23, 24.

In order that the invention might be understood, the details of the preferred embodiments have been set forth and particularly described, but it is not desired to be limited to the details of the construction shown except as specified in the claims since it will be apparent that persons skilled in the art may resort to various modifications without departing from the purpose and spirit of my invention.

I claim:

1. In a composite wooden baker's peel, an inner core having a tapered tip, veneered wooden sheets of uniform thickness attached to each other and to the tapered tip at each side, overlapping the core and contacting with each other beyond the tip, the grain of the veneer of corresponding sheets on opposite sides of the tip being parallel and at right angles to that of the adjacent veneer sheet to prevent warping of the peel when it is

heated, and the grain of the veneered sheets in the tip being at an angle of forty-five degrees with respect to the edge of the tip to form a thin hard wearing edge.

2. In a composite wooden baker's peel, an inner core with a tapered tip, veneered wooden sheets of uniform thickness attached to each other and to the tapered tip at each side, overlapping the tip end of the core, the veneered sheets contacting with each other and having the same number of layers on each side of the core and the grain of the veneer of corresponding sheets on opposite sides of the core being parallel and at right angles to the grain of the next adjacent sheet or sheets to prevent warping of the peel when it is heated, the grain of the layers at each side of the core each being at right angles to the grain of the next layer or layers and at an angle of forty-five degrees to the edge of the tip of the peel.

3. In a composite wooden baker's peel, an inner core with a tapered tip, veneered wooden sheets attached to each other and to the tapered tip at each side, overlapping the core, the grain of the corresponding sheets on opposite sides of the core being parallel and at right angles to the next adjacent veneered sheet on the same side of the core, the portions of the veneered sheets beyond the core tip being beveled and adhesively secured together, the extremities of the sheets meeting and forming a sharp projecting edge in which the grain of each of the sheets is at an angle of forty-five degrees to the extremity of the peel.

4. In a composite wooden baker's peel, an inner core with a tapered tip, veneered wooden sheets attached to each other and to each side of the tapered tip, the outer ends of the sheets being beveled and abutting each other, overlapping the core, and adhesively secured together, producing a sharp outer extremity, the grain in each sheet at one side of the core being at right angles to that of the next sheet, the grain in corresponding sheets on opposite sides of the core being parallel and in engagement beyond the core, and the grain in all of the sheets being at approximately an angle of forty-five degrees to the exposed extremity of the tip to provide a thin, hard, wearing edge.

5. In a composite wooden baker's peel, an inner core with a tapered tip, ply wood sheets, each consisting of several layers of veneer attached at each side of the tip and beveled at the inner sides of the outer ends so that opposite corresponding layers meet beyond the ends of the core, the said corresponding layers having parallel grains which are at right angles to the grains of the adjacent layers, and the grains of all the layers being at an angle of forty-five degrees to the tip edge of the peel.

HENRY L. SCHROEDER.
